UNITED STATES PATENT OFFICE.

ELLIS F. ORNER, OF GOWEN CITY, PENNSYLVANIA.

DESIGN FOR A PLANT-PROTECTOR.

SPECIFICATION forming part of Design No. 25,490, dated May 12, 1896.

Application filed March 23, 1896. Serial No. 584,553. Term of patent 14 years.

To all whom it may concern:

Be it known that I, ELLIS F. ORNER, a citizen of the United States, and a resident of Gowen City, in the county of Northumberland and State of Pennsylvania, have invented a new and original Design for Plant-Protectors; and I do hereby declare that the following is a full, clear, and exact description of the invention, which will enable others skilled in the art to which it appertains to make and use the same.

In the accompanying drawing, the figure represents a perspective view of a plant-protector made according to my design.

The design relates to cylindrical plant-protectors; and the leading feature consists in the cylindrical body provided at the upper end with a series of inwardly-bent tapering fingers with circular openings at the bases thereof, and below said openings an ornamental bead, whereby a neat and pleasing appearance will be given to the device.

In the said drawing the reference-numeral 1 designates the cylindrical body, and 2 ornamental bosses.

The numeral 3 designates the tapering inwardly-bent fingers at the upper end, and 4 a series of circular holes at the base of said fingers, or where they join said body. Below said holes is a raised bead 5, formed with a number of ornamental scrolls 6.

What I claim is—

The design for a plant-protector herein shown and described.

In testimony that I claim the foregoing as my own I have hereunto affixed my signature in presence of two witnesses.

ELLIS F. ORNER.

Witnesses:

I. M. GASKINS,
D. C. KASEMAN.
